Wm. F. Folke

INVENTOR,
James Charlton,
By Louis Dager, Esq.
Attorney.

UNITED STATES PATENT OFFICE.

JAMES CHARLTON, OF HOUSTON, TEXAS.

CAR-DOOR.

SPECIFICATION forming part of Letters Patent No. 404,259, dated May 28, 1889.
Application filed August 10, 1888. Serial No. 282,478. (No model.)

To all whom it may concern:

Be it known that I, JAMES CHARLTON, a citizen of the United States, residing in Houston, Harris county, State of Texas, have invented certain new and useful Improvements in Railway-Car Doors and in the Method of Operating the Same; and I do hereby declare that the following is a full, clear, and exact description of the same.

10 The invention relates to improvements in hanging and sliding car-doors; and it consists in the construction and novel combination of parts hereinafter described, illustrated in the accompanying drawings, and pointed out in 15 the appended claims.

In the accompanying drawings, Figure 1 represents a side view of a railway-car having a door embodying the invention attached. Fig. 2 represents an edge view of the door, 20 showing its side bevels. Fig. 3 represents a vertical section on the line $x-x$ of Fig. 1.

Referring to the drawings by letter, A designates the side of a railway-car having the sill a extending longitudinally adjacent to 25 the edge of its floor, and the door-opening a' , having beveled or inwardly-converging side edges, and its upper and lower edges, a^2 a^3 , respectively, which are parallel, inclining inward and upward.

30 B is the car-door, having beveled edges b and fitting accurately in the opening a' in such manner that the outer and inner surfaces of the door are flush with those of the car. The door has secured to it near its 35 lower edge and in its central vertical line a guide-staple, b' , for the bolt, hereinafter described.

C is a fulcrum-bracket secured to the door in said line, and preferably a little below the 40 center of the door. Upon said bracket is pivoted the operating-lever D, to which is pivoted, a short distance from the pivotal point thereof, the link-rods d d , the lower ends of which are pivoted to the upper end of the 45 vertical bolt E. The said bolt passes through the guide-staple b' and enters the keeper e, secured to the sill a . It is evident that by raising the outer end of the lever D the bolt will be lifted out of its keeper and the door 50 will be unlocked.

f is a link-rod pivoted at its lower end upon the operating-lever D on the same pin that

connects the link-rods d therewith, and at its upper end to a crank-arm, f' , standing from the central part of the transverse shaft 55 F, which is journaled in bearings in the hanging hinge-joints G. The said joints are composed of the following parts:

H are lower hinge-plates secured to the outer surface of the door B by bolts or otherwise at equal distances from the side edges thereof. The said plates are sleeved at their upper ends, at h , to form, with the corresponding pintle-pins, h' , and the lower sleeved ends, i , of the upper free hinge-plates, I, the hinges 60 proper of the car-door. The said plates I are sleeved at their upper ends, i' , to form, with the lower sleeved ends, j , of the hanger and rider plates J, the joints j' , which form the 65 bearings for the shaft F, the latter constituting the pintles for said joints j' . The said hanger and rider plates have their upper 70 portions, j^2 , bent over the upper edge, k , of the longitudinal way-beam K, which is secured to the side of the car above the door 75 and immediately below the roof. The said upper edge, k , is preferably flat, and the bent-over portions of the hanger-plates are then 80 rectangular in cross-section and each provided with opposite bearing-openings L, consisting of the larger circular lower portions, l , and the smaller circular upper portions, l' , that are the true bearings for the journals m of the anti-friction rollers M, that travel on the upper edge of the way-beam K. By means 85 of the openings L the door can be lifted from the rollers M till the bent-over parts of the hanger-plates are free of the beam K to dismount the car-door. The said rollers M are less in diameter than the lower portions, l , of 90 the openings L, so that if one of said rollers should be broken the corresponding side of the door may be lifted, the said roller removed, and a perfect one substituted therefor.

It is evident that when the bolt is lifted by 95 the lever D the same motion will, on account of the described construction of the hinge-joints G and by means of the drawing down of the link-rod f , draw the car-door downward and outward till it is clear of the side of the car and can be moved laterally upon the way-beam K in the ordinary well-understood manner.

The mechanism as described is simple,

strong, and effective, and will be found very convenient in practice.

Having described my invention, I claim—

1. The combination, with the car having the door-opening with its upper and lower edges parallel and inclined upward and inward, and the bolt-keeper secured to the sill of the car, of the door having correspondingly inclined upper and lower edges, the guide-staple b' and fulcrum-bracket C , secured to the door at proper points, the operating-lever pivoted to said bracket, the link-rods d and bolt E , the link-rod f , pivoted at its lower end to the operating-lever and to the link-rods d at the same point, the shaft F , having the arm f' , pivoted to the rod f , and the hanging hinge-joint G , of which the shaft F forms the pintles, substantially as specified.

2. The combination, with the car-door B and the way-beam K , having the flat upper edge, k , of the operating-lever D , pivoted to

the fulcrum-bracket C , secured to the door, the link-rod f , the shaft F , having the arm f' , the hanging hinge-joints G , composed of the plates H , having their upper edges sleeved at h , the plates I , having their lower edges sleeved and connected to the plates H by pindle-pins, and the plates J , sleeved at their lower ends and making joints with the plates I , of which joints the shaft F forms the pindle, and the anti-friction rollers M , the journals of which have bearings proper in the smaller circular upper portions, l' , of the openings L in the bent-over upper parts of the plates J , which openings have the larger circular lower parts, l , of greater diameters than those of said rollers, substantially as specified.

JAMES CHARLTON.
